Primary Examiner — Michelle E. Wilson*Assistant Examiner* — Caitlin A Laverty(74) *Attorney, Agent, or Firm* — Hawaii Patent Services; Nathaniel K. Fedde; Kenton N. Fedde(57) **CLAIM**

The ornamental design for a key chain, as shown and described.

DESCRIPTION

FIG. 1 is a front, top perspective view of a key chain, showing my new design;

FIG. 2 is a rear, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The dashed broken lines in the figures are for the purposes of illustrating portions of the key chain that form no part of the claimed design.

1 Claim, 8 Drawing Sheets(56)
